UNITED STATES PATENT OFFICE.

ORA L. LANCE, OF LOS ANGELES, CALIFORNIA.

CIGAR OR CIGARETTE CASE.

1,201,474.

Specification of Letters Patent. Patented Oct. 17, 1916.

Application filed January 5, 1915. Serial No. 607.

To all whom it may concern:

Be it known that I, ORA L. LANCE, a citizen of the United States, residing at Los Angeles, in the county of Los Angeles and 5 State of California, have invented new and useful Improvements in Cigar or Cigarette Cases, of which the following is a specification.

The present invention relates to improvements in cigar and cigarette cases, the object 10 of the invention being to provide such a case of simple and inexpensive construction having a device for holding the cigars or cigarettes in a position for withdrawal by the 15 smoker.

In the accompanying drawings, Figure 1 is a perspective view of an open cigarette case embodying my improvements; Fig. 2 is a broken perspective view of the two sides 20 of the case separated from each other; Fig. 3 is a broken sectional view through a hinged portion thereof; Fig. 4 is a similar view through a marginal portion thereof; Fig. 5 is an enlarged broken sectional view through 25 a cigarette holder in the case; Fig. 6 is a similar view taken on a different plane; Fig. 7 is a broken sectional view of the cigarette case and holder showing the holder in its normal position close to a side of the case; Fig. 8 is a similar view thereof showing the 30 holder in a raised position; Fig. 9 is an end view of the cigarette case closed; Fig. 10 is a plan view of a blank from which a side of the cigarette case is formed; Fig. 11 is a 35 sectional view of said blank and of dies for bending the same; Fig. 12 is a sectional view of the blank and dies after the first bending has been effected; Fig. 13 is a similar view of the blank and a second set of dies before 40 the second bending is effected; Fig. 14 is a similar view of said blank and said second set of dies after the second bending has been effected; Fig. 15 is a perspective view of the two sides of the cigarette case, closed. 45 Referring to the drawing, 1 indicates a blank from which a side of the cigarette case is formed. In said blank, close to one end thereof, are formed a short rectangular hole 2 near one side, and a longer rectangular hole 3 near the opposite side, said holes 50

2 and 3 being spaced apart a distance substantially equal to the length of the hole 2, and the hole 3 being also at a distance from its nearer side a little greater than the length of the hole 2. Each blank is first bent so 55 as to have curved margins, as shown in Fig. 12, by means of two dies 4 and 6. The blank is then inverted, as shown in Fig. 13, and placed upon a female die 7 of such shape, as shown at 8, as to form hinges 9 in the end 60 in which the holes are formed, and a male die 10 is then placed over the blank, and, by pressure of the male die, the middle portion of said blank is inverted, or turned inside out, the convex side thereof becoming 65 concave, as shown in Fig. 13. There is thus formed around each side of the case a rim 11, bent outwardly and back upon itself. This result could not be obtained by a direct bending outwardly and backwardly upon 70 itself of the marginal portion of the concave side of the case, for, by such an operation, the metal of the margin would be broken or torn apart. The same effect, however, is produced by my improved process 75 by retaining said marginal portion unchanged, and turning the middle portion of the case inside out. This method of forming a rim on a concave article is believed to be new. 80

The parts 5 and 12 respectively between and at the side of the holes 2 and 3, in each half of the cigarette case are, by this process, formed into knuckles, and the holes 2 and 3 of said halves are adapted to receive 85 the knuckles 5 and 12 of the other halves, as clearly shown in Fig. 15. The longer holes 3, however, are not completely filled by the knuckles 5, and the unfilled parts 13 (Fig. 15) are used to secure to the cigarette case a 90 holder 14. Said holder consists of two U-shaped sections 16, 17, which, to hold them together, are formed with pairs of knuckles 18, 19 and a hinge pin 21 is passed through the two pairs of knuckles 18 and 19 to pivot 95 the two sections together. The section 17 is also extended to form a bearing 22 which surrounds the hinge pin 23 of the cigarette case, said bearing being formed with a tail 24. A spring 26 is coiled around the hinge 100

pin 23, and one end bears against the section 16 and the other end against the inner surface of the adjacent half of the cigarette case, thus pressing said section 16 toward the 5 section 17 and holding securely cigarettes placed between said sections. The free ends of the U-shaped sections are bent first inward, as shown at 27, to form retainers for the cigarettes, and then outward, as shown 10 at 28, to facilitate the insertion of the cigarettes into the holder.

The holder tends to remain in contact with one side of the cigarette case, by reason of the pressure of the coiled spring, as shown 15 in Fig. 7. But when the cigarette case is opened sufficiently wide the holder is raised to a central position, as shown in Fig. 8, by pressure against the tail 24 by the narrow portion 29 between the hole 3 and the adjacent end of one of the blanks.

I claim:—

1. In an article of the character described, in combination with two case sections each having knuckles and holes to receive the 25 knuckles of the other case section, a hinge pin extending through said knuckles, and a holder consisting of two sections hinged together, one of said holder sections being extended to form a knuckle, fitting closely 30 around, and vibratable on, said hinge pin.

2. In an article of the character described, in combination with two case sections hinged together to form a case, a holder within the case consisting of two sections hinged together, and a spring acting to press the two 35 holder sections together and against one of the case sections.

3. In an article of the character described, in combination with two case sections hinged 40 together to form a case, a holder within the case consisting of two sections hinged together, and a spring acting to press the holder against a case section.

4. In an article of the character described, 45 in combination with two case sections each having knuckles and holes to receive the knuckles of the other case section, a holder consisting of two sections hinged together, one of said holder sections being extended 50 to form a knuckle, a hinge pin extending through said knuckle and the knuckles of the case sections and a spring coiled around said hinge pin, and of which one end bears against the other holder section and the 55 other end bears against the adjacent case section.

5. In an article of the character described, in combination with two case sections hinged together to form a case, a holder within the 60 case consisting of two sections hinged together, one of the holder sections being extended outside the case, a case section having an outer portion located to engage said

extended portion of the holder to move the holder with reference to the case.

6. In an article of the character described, 65 in combination with two case sections hinged together to form a case, a holder consisting of two sections hinged together, one of said holder sections being hinged coaxially with the case, one of the holder sections being extended outside the case, a case section having an outer portion located to engage said extended portion of the holder to move the holder with reference to the case.

7. In an article of the character described, 70 in combination with two case sections each having knuckles and holes to receive the knuckles of the other case section, a holder consisting of two sections hinged together, 80 one of said holder sections being extended to form a knuckle, a hinge pin extending through said knuckle and the knuckles of the case sections, said holder section being extended beyond said knuckle to form a bearing, 85 a case section having an outer portion located to engage said extended portion of the holder to move the holder with reference to the case.

8. In an article of the character described, 90 in combination with two case sections each having knuckles and holes to receive the knuckles of the other case section, a holder consisting of two sections hinged together, one of said holder sections being extended to 95 form a knuckle, a hinge pin extending through said knuckle and the knuckles of the case sections, said holder section being extended beyond said knuckle to form a bearing, a case section having an outer portion 100 located to engage said extended portion of the holder to move the holder with reference to the case, and a spring coiled around said hinge pin, and of which one end bears against the other holder section and the 105 other end bears against the corresponding case section.

9. In an article of the character described, 110 in combination with two case sections each having knuckles and holes to receive the knuckles of the other case section, a holder having sides which can be spread apart and one of which is extended to form a knuckle, 115 a hinge pin extending through said knuckle and the knuckles of the case sections and a spring coiled around said hinge pin, and of which one end bears against the holder and the other end bears against the adjacent case section.

10. In an article of the character described, 120 in combination with two case sections each having knuckles and holes to receive the knuckles of the other case section, a holder extended to form a knuckle, a hinge pin extending through said knuckle and the 125 knuckles of the case sections, said holder be-

ing extended beyond said knuckle to form a bearing, a case section having an outer portion located to engage said extended portion of the holder to move the holder with reference to the case, and a spring coiled around said hinge pin, and of which one end bears against the holder and the other end bears against a case section.

In testimony whereof I have hereunto set my hand in the presence of two subscribing witnesses.

ORA L. LANCE.
